N. S. Vedder & E. Ripley, of Troy, N. Y.

Assignors to

J. F. Filley, of St. Louis, Mo.

Letters Patent No. 690. Dated Jan'y 23rd 1855.

The schedule referred to in these Letters Patent, and making part of the same.

To all whom it may concern,

Be it known that we, N. S. Vedder, and Ezra Ripley, of Troy, in the County of Rensselaer, and State of New York, have invented or produced a new and original design of Parlor Stove plates, which we call the "Magnolia", and we do hereby declare that the following is a full, clear, and exact description of the same, reference being had to the annexed perspective drawing and letters of reference marked thereon, forming part of this specification.

Our design of parlor stoves is composed as follows viz: A. is the top plate, with ornamental border (a), roses (b. b.) at each side of boiler hole, and the surface (c. c.) of checkered or diamond work. B. is the front plate, decorated with the scrolls (d. d.) at top (e. e.) at bottom, (f.) is a center ornament of roses, diamond work and moulding (g.) is a frog at top of plate, (h. h.) is border moulding or fillet (i. i.) diamond or checkered work, (i'. i') moulding connecting top and bottom scrolls. C. is the end plate with the center ornaments of rose (j.) scrolls (k) and diamond work (l.), (m) is top ornament, (n) and (o) bottom ornaments. D is the bottom plate, with the ornamental moulding (p. p. p.) disposed on its edge.

Having described our design of parlor stove plates, what we claim as new and desire to secure by letters patent is the ornamental design and configuration of parlor stove plates, such as herein described and represented in

Dec. 690
